CLAIM

The ornamental design for an icon for a display screen, as
shown and described.

DESCRIPTION

FIG. 1 is a top, front, right side perspective view of an icon
for a display screen showing my new design;

FIG. 2 is a front elevational view thereof;

FIG. 3 is a front elevational view thereof, the icon is shown
separately for clarity of illustration; and,FIG. 4 is a front elevational view thereof, the icon is shown
separately for clarity of illustration, on a reduced scale.The broken line drawing of a display screen in FIGS. 1 and
2 shows the environment on which the icon is displayed and
forms no part of the claimed design.
